(57) CLAIM

The ornamental design for a cigar lighter, as shown and described.

DESCRIPTION

FIG. 1 is a top perspective view of cigar lighter showing my new design.

FIG. 2 is a front view thereof.

FIG. 3 is a rear end view thereof.

FIG. 4 is a left end view thereof.

FIG. 5 is a right view thereof.

FIG. 6 is a bottom view thereof; and,

FIG. 7 is a top view thereof.

The broken lines shown in the drawings illustrate portions of the cigar lighter that form no part of the claimed design.
